UNITED STATES PATENT OFFICE.

FRANKLIN AUGUSTUS REECE, OF MANCHESTER, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,190,583.

Specification of Letters Patent.

Patented July 11, 1916.

Application filed November 8, 1913. Serial No. 799,855.

To all whom it may concern:

Be it known that I, FRANKLIN A. REECE, a citizen of the United States, residing at Manchester, in the county of Essex and 5 State of Massachusetts, have invented certain new and useful Improvements in Buttonhole-Stitching Machines, of which the following is a specification, reference being had therein to the accompanying drawing.

10 This invention relates to buttonhole stitching machines and more particularly to machines adapted for over-seaming the edges of buttonholes.

The invention, which pertains more particularly to the stitching mechanism, is for convenience shown applied to the general type of buttonhole stitching machine known as the "Reece" buttonhole machine, wherein a stitch frame carrying the stitching mechanism and a worm support are relatively movable to enable the stitching to be carried along the edges of a buttonhole. Many details of the machine other than stitching mechanism are, for convenience, omitted 20 herefrom, but may be supplied by reference to such prior known machines as are illustrated, for example, in Patent No. 695,039, granted March 11, 1902, upon the invention of W. W. Dixon.

30 An object of the present invention is to afford in a buttonhole stitching machine of the type referred to, or of other types, an efficient and novel stitching mechanism, particularly one adaptable to the species of machine in which an eye-pointed needle carries an upper thread, and a shiftable stock carries the needle which manipulates an under thread in coöperation with the needle carrying the upper thread.

40 A further object hereof is to improve in different ways the mode of coöperation between the parts above and below the work.

Another object is to improve the action of the machine and its durability, by the 45 employment of a straight under needle coöperating with a straight upper needle.

Another object is to improve and simplify the machine by dispensing with the usually employed looper beneath the work coöperating with the under needle.

Another object is to permit the dispensing with the looper by reason of giving to the under needle a special motion or action not heretofore employed.

55 Another object is to improve the cooper-

ation between the upper and under needles by operating both of them in vertical planes in the manner hereinafter to be described.

Other objects and advantages of the present improvement will appear in the herein- 60 after following description or will be obvious to those skilled in the art.

First will be described one or more preferred embodiments of the present improvement as illustrative of the principles involved and thereafter the novel features will be pointed out in the appended claims.

In the accompanying drawings forming a part hereof Figure 1 is a partial right-hand elevation of a buttonhole stitching machine 70 of the type before referred to and embodying the present improvements. Fig. 2 is a left-hand elevation of the under sewing mechanism detached including the shiftable stock and the parts carried thereby. Fig. 3 75 is a front elevation partly in vertical cross section taken on the plane 3—3 of Fig. 4. Fig. 4 is a right-hand elevation of the under sewing mechanism. Fig. 5 is a front elevation of the portion of the machine shown in 80 Fig. 1, taken partly in central cross section to show the interior structure. Fig. 6 is a top plan view of the under sewing mechanism with the forward side thereof at the bottom of the drawing. Figs. 7 and 8 show 85 details of the fittings of the under needle. Figs. 9, 10 and 11 show diagrammatically the motions of the under needle and carrier. Figs. 12 to 18 show in successive steps the mode of coöperation between the upper and 90 under needles. Fig. 19 shows a left-hand elevation corresponding to Fig. 2 but disclosing a modified embodiment of the improvement. Fig. 20 is a front elevation partly in central section of the under mechanism shown in Fig. 19. Figs. 21 to 24 show 95 in successive steps the mode of coöperation between the upper and under needles of Figs. 19 and 20.

Similar reference numerals designate corresponding parts in the different figures of the drawings.

While in some aspects the present improvements might be employed in any two-thread buttonhole stitching machine having 105 a feed or relative movement between the work clamping and stitching devices the improvements were especially designed and are particularly useful in connection with a machine having coöoperating upper and under 110

needles, the under needle with its fittings and actuating parts being carried upon a stock which shifts during the sewing operations; for example, shifts longitudinally or 5 in a rotary manner or both.

In referring to "buttonhole stitching" it is not intended to limit the invention to the production of buttonholes since that type of stitching may be applied along the edges of 10 eyelets or other holes or edge portions of fabric. For convenience the work and the work support, to be described herein, will be referred to as horizontal and the respective needles as upper and under needles but it is 15 to be understood that such words are used merely in a relative sense.

Specifically the herein illustrated example of the present invention may be described as follows: A work clamp frame 30 20 and a stitch mechanism frame 31 are relatively movable in any desired manner for the purpose of enabling the stitching to advance along the work. The work clamp frame 30 may be considered as stationary. 25 It is provided with suitable clamping devices indicated at 32. A cutting device 33 may be employed for the purpose of descending toward the work support or clamp frame 30 to cut the slit afterward to be 30 stitched into a buttonhole, and the cutter 33 may be opposed by an anvil 34 seen in Figs. 2, 3 and 4 and indicated in Fig. 1.

The stitch frame 31, already referred to, is only partially shown but it will be understood to be capable of relative movement, it moving longitudinally or forwardly and rearwardly and also laterally at times with respect to the clamp frame 30; and the stitch frame has portions extending both below 40 and above the level of the work, the upper portions having a forwardly extending arm, a portion of which 35 is shown in Figs. 1 and 5. This overhanging portion 35 of the stitch frame carries the needle bar 36 by 45 which the upper needle 37 is carried in its vertically reciprocating movements as will later appear. The needle 37 is eccentric with relation to its bar or carrier so that the needle may be shifted slightly circularly 50 when the shifting stock, hereinafter to be referred to, oscillates.

The portion of the stitch frame 31 which is below the work level has at its front extremity a casing 38 containing cams for 55 performing certain operations. In the forward and backward movements of the stitch frame bolts 39 on the cam casing serve to steady and guide the stitch frame by engaging in sliding contact with the surfaces or 60 ways 40 on the clamp frame 30.

Opposed to the upper needle 37 and carried by the stitch frame beneath the work is the under stitching mechanism. There may be a relative shifting of the stitching mechanism with respect to the work clamp and

this may be effected by mounting the under stitching mechanism upon a shiftable stock 45. The stock may, for example, shift circularly or oscillate about its own vertical axis. Means are shown for giving the stock 70 45 support and bearing in its circularly shifting movements. Thus a circular bearing 46, formed at the front of the cam casing 38 is engaged by the circular upper portion of the stock, while a depending hanger 47 is 75 fitted to give support and bearing to the circular lower portion of the stock as more clearly seen in Fig. 5.

It is proposed to circularly shift the stock in such manner and at such times as the particular work may require by means of mechanisms which serve also to rotate the upper needle carrier 36 thus correspondingly circularly shifting the upper needle. A gear 50 is shown secured to the lower portion of 80 the stock 45 by means of a nut, the gear's hub engaging within the hanger 47 as before explained, for the purpose of a lower bearing. The gear 50 is engaged by a second gear 51 shown as a partial gear or rack; the 85 toothed rack 51 is carried on a two-armed lever 52 Fig. 1 which permits the rack to oscillate and thereby circularly shift the stock. The rearward arm of the lever 52 is seen engaged by another lever 53 in such a manner that the latter may operate the former. The lever 53 is shown secured at the lower end of an upright shaft at 54 while a stud 55 projects from the lever 53 into the cam casing 38 so that the cam therein may 90 cause the swinging of the lever. The parts described may be suitably connected by connections extending above the work level so as to cause the shifting of the upper needle 37 in exact accordance with the shifting of 95 the stock 45.

It is intended that the under stitching mechanism carried on the stock 45 shall be operable whether the stock be shifting or at rest. Convenient connections for this 100 purpose include an actuator 60 which is shown in the nature of an upright hollow bar located centrally or axially of the stock and capable of rapid up and down vibration. To effect such vibration of the actuator it is shown provided with a ball and cup device or joint 61 at its lower end through which the actuator is engaged by a lever 62 having a forked forward end straddling the ball and cup device, such lever being 110 intermediately pivoted at the lower part of a pair of opposite side brackets 63. The lever 62 extends rearwardly beyond the pivot and at its rear end has a connection such as rod 64 by which it is actuated from 120 a suitable cam or other automatic portion of the machine so as to cause rapid up and down movements and thereby effect the vibration of the actuator.

There have now been described all of the 130

parts to be referred to with the exception of those carried on the stock 45 serving as fittings for the under needle 70 or coöperating therewith. A suitable under needle carrier 71 is shown as extended in alinement with the needle although it might stand relatively differently.

At the upper portion of the stock 45 is shown a throat plate 72 carried upon an exten-
10 sion 73. It will be understood that the under needle 70 reciprocates generally upwardly and downwardly through the throat plate in coöperation with the upper needle. While possibly different forms of stitches
15 could be made the general mode of operation of the described example of the present invention is that the under needle when above the work presents to the upper needle a loop of under thread, the upper needle entering such loop, descending, penetrating the work, and when below the work presenting or affording a loop of upper thread which the under needle, after descending, is caused to enter on its succeeding ascent,
20 so that with perhaps the assistance of proper take-up devices the two threads are alternately interlocked above and below the work and set, to produce an overseam or button-hole stitch.

25 Before describing the actual fittings of the under needle as seen in Figs. 1, 2 and 8, the general nature of the needle's operation will be best explained from the diagrams Figs. 9, 10 and 11. Fig. 9 shows the under
30 needle and carrier in the position where the needle is about to enter the throat plate or pass through the plane of the work or the slit therein. When the needle passes above the work it is preferred to tip it laterally
35 toward the path of the upper needle and this tipping may be conveniently attained by moving the under needle up and down substantially in an arc or curved path. Instead of fitting the under needle by means
40 of slideways for this motion a link motion is shown designed to give the desired movement. Thus the under needle carrier 71 is indicated in the diagrams as having a link 74 extending from its lower end to a fixed
45 pivot or center at 75 while the carrier's upper end is shown as connected by a link 76 with a pivot or center 77. If the two links were parallel and of the same length the needle and carrier would have no tipping motion and, therefore, the links are
50 otherwise constructed. When moved upwardly the action of the links will be as indicated in Fig. 10 to cause a substantial tipping. The motion of the needle and carrier
55 between the positions of Figs. 9 and 10 may be termed the regular motion and that motion is controlled solely by the two links
60 swinging about the two centers 75 and 77. Heretofore in this type of machine it has
65 been customary to employ a special looper

device beneath the work for taking a loop of thread from the upper needle and delivering it to the under needle. In the mechanism described herein, however, the under needle when below the work is given such
70 a lateral movement as to enable it, without the aid of the looper, to enter a loop of thread on the upper needle, namely, by moving beyond the path of the upper needle and during its return entering the loop before again ascending. This lateral motion of the under needle may be considered an extra motion, and to effect that in the described construction a different device is
75 herein brought into play. Such device is
80 one enabling one of the pivots 75 or 77, to relatively shift sufficiently to cause or enable the extra or lateral movement of the under needle beneath the work. The center or pivot 77 is shown rendered capable
85 of shifting to a new center or position 78 (Fig. 11) by means of a third link 79 which, itself, is fixedly pivoted at 80 and at its other end affords a pivot and guide for one end of the link 76. The result of this
90 comparatively simple 3-link motion is that the under needle and carrier when brought downwardly to the position of Fig. 9 may be shifted laterally to the position of Fig.
95 11 for their extra movement and return to the position of Fig. 9 before again ascending to the position of Fig. 10.

Having explained from the diagrams the general nature of the motion of the under needle, reference will now be made particularly to Figs. 2, 3, 4, 7 and 8 for the details of the actual structure. Before, however, describing the needle fittings it will be clearer to first describe the following auxiliary devices carried by the stock. The upper end 100 of the hollow actuator 60 has an aperture 93 constituting an exit for the under thread which enters the lower end of the actuator. Passing from the exit 93 the thread extends downwardly to a tension 94, around said tension and upwardly to the extremity of the 105 take-up lever 95 which is capable of shifting to and fro in harmony with the movements of the needles. The take-up lever is pivoted upon a boss 96 and has associated with it a
110 spring 97 tending always to press the take-up lever leftward in Fig. 3. A projecting pin 98 on the actuator contacts the take-up lever and forces it to the right against the opposition of spring 97 at the proper times 115 to give up and take up the under thread. From the extremity of the take-up the thread passes to a thread eye 99 at the top of the stock and from thence the thread passes first to the lower and then to the 120 upper eye of the eye-pointed under needle 70.

125 It will be particularly noted that the fittings of the under needle are such that the needle in all of its swinging movements re-

mains in a single vertical plane relatively to the stock. It has heretofore been deemed necessary to move the under needle on an inclined plane for one reason or another but herein stress is laid on its movement in a vertical plane as this effects a great simplification in the nature of the connections for actuating the needle. At the same time the character of the stitch produced in the machine is not materially affected. As will be seen by inspection of the drawings the vertical plane in which the under needle oscillates stands in very close proximity to the vertical line constituting the path of the upper needle so that at both their upper and lower positions the two needles are in very favorable relative positions for exchanging thread loops.

The link motion diagrammatically illustrated in Figs. 9, 10 and 11 and above described will be seen to be mechanically worked out in Figs. 2, 3, 4, 7 and 8. In Fig. 3 the link motion is shown substantially complete in front view. Figs. 7 and 8 combined constitute a dissection of the mechanism, two of the numbers 71, 76 being assumed to have been bodily detached and so illustrated in Fig. 7, while Fig. 8 shows the remainder of the mechanism after such detachment. The link 74 from the lower end of the carrier 71 is shown of a curved form for the purpose of clearing other parts of the mechanism to avoid conflict. The upper end of the link 74 has the center of rotation or stud at 75 relatively fixed in position by reason of being pivoted to an upstanding extension 83 of the stock, located substantially opposite the extension 73 which supports the throat. The link 76 from the upper end of the carrier 71 extends to a movable center or stud located at 77 (see Fig. 7) which is capable of shifting to position 78 (see Fig. 8) by reason of a guiding arm 79 having its center or pivot stud at 80 upon the extension 83. For actuating this link combination and causing reciprocating movements of the under needle the link 74 is shown provided with a projection 81 for the purpose of properly locating the pivotal connection between the projection 81 and the link 82 which at its lower end is shown pivotally connected to the actuator 60. These various parts whose forms are shown in Figs. 3, 7, and 8, have their relative positions indicated in Figs. 2 and 4, the various pivotal connections having sometimes a slight and sometimes an extended horizontal dimension so as to enable all of the parts to be snugly accommodated within the small space that is available.

Manifestly the swinging of the upper pivot of the link 76 between the positions 77 and 78 must be effectively controlled. The parts show the link in its ordinary position during which the up and down needle move-

ments are effected. A stop is provided for the link in this position and this stop may conveniently comprise the hub 84 of the link 74 at the pivot point 75 of the latter. The hub of link 76 bears in direct contact with the hub of link 74. To prevent any undue tendency of displacement from this normal position the arm 79, which controls the center of swinging of link 76, is provided with an extension 85 acted upon by a short strong spring 86. A spring 87 is also shown effecting a leftwise pulling upon the carrier 71 when the latter has been displaced to the Fig. 11 position. This spring 87, therefore, supplements or assists the action of the spring 86 by tending to restore the link mechanism to the position indicated in Figs. 3 and 9. Incidentally the spring 87 also prevents any possibility of a binding as between the carrier 71 and link 76 when the two approach a position of alinement.

For displacing the center of swinging of link 76 from position 77 to 78 and thereby throwing the carrier and needle laterally to the Fig. 11 position a convenient device is a toe 88 formed on or carried by the link 74 or the hub thereof as shown so that the extreme downward swinging movement of the link 74 causes the toe 88 to bear upwardly on the hub of link 76 thereby displacing the same from position 77 to 78. It will be understood that the complete downward movement of the actuator 60 brings the toe 88 into action, thereby swinging the under needle laterally to Fig. 11 position, while the return or upward movement of the actuator first acts to restore the linkage to the position of Figs. 3 and 9 and thereupon swings the needle and carrier to the position above the work as in Fig. 10.

It will be noted that the described linkage in its ordinary range of motion affords an effective means of swinging the needle in a curved arc in such way that the needle has an efficient movement, entering the work plane perpendicularly and swinging around to its tipped position of Fig. 10 by a movement throughout which some portion of the needle always intersects at the same point in the work level.

The preferred mode of action as between the upper and under needles 37 and 70 is indicated by the successive diagrams in Figs. 12 to 18 inclusive.

Fig. 12 shows the needles in what may be termed their normal positions, both being disengaged from the work. The upper needle has almost arrived at its highest point, the under needle stands vertically beneath the work and is about to enter the throat plate and to pass through the plane of the work or the slit of the buttonhole. Both needles are, as stated, eye-pointed.

Fig. 13 shows the under needle having risen through the work carrying the under

thread with it and the needle has at the same time commenced to tip toward the path of the upper needle, it being understood that the under needle moves in a vertical plane in close proximity to the vertical path of the upper needle although, as will hereinafter appear, this relative disposition of the needles may be altered. The upper needle is shown as having commenced 10 its descent.

Fig. 14 shows the under needle having ascended and tipped to its extreme and having then withdrawn slightly, such withdrawal causing a fullness or loop in the 15 thread, thus better positioning the thread to receive the upper needle. The upper needle is shown as having descended farther and being about to enter the loop of under thread. It will be noted that there is thus 20 direct coöperation between the needles above the work, no looper being employed to cause the interchange of loops or interlocking of threads.

Fig. 15 shows the under needle having 25 retracted nearly to normal position, while the upper needle has descended through the under thread loop, penetrating the work, and passed to a position beneath the work.

Fig. 16 shows the position of the needles 30 after a further operation in which the under needle has passed through its normal position and has moved relatively laterally below the work by, the extra motion caused by the swinging of link 79; to a position 35 beyond the path of the upper needle. In the meanwhile the upper needle has completed its full descent.

Fig. 17 shows the upper needle as having 40 started to ascend thus causing a fullness or loop of upper thread which is being entered by the under needle on its return toward normal position. Thus there is direct coöperation between the needles below the work, the needle movement serving to 45 interlock the threads without the aid of a looper.

Fig. 18 shows the result of the continued 50 movement of the needles, both of them continuing toward the normal position for the purpose of repeating the interlocking of threads above the work. Thus the upper and under threads are rapidly interlocked, first above and then below the work, forming a lock stitch, which, at each needle 55 movement, is tightened or set by the action of proper take-ups for the two threads.

Referring now to the modification of Figs. 19 to 24 the mechanism is there shown altered in several respects. The upper needle 60 37 as before, reciprocates in a straight vertical line, while there is below the work the oscillating stock 45 carrying the under stitching mechanism. The actuator is no longer a vertically sliding rod but includes 65 a part driven by an upright actuator link

100. This link may be generally axially located and at its upper end connected to the actuator arm 101 pivoted for convenience by means of a hub 102 having bearing 103 at the two sides of the stock. The link 100 is 70 connected by a ball and cup device to the actuator arm 101 and at its lower end by a similar device 105 to the vibrating lever 62. The link 101 is adjustable in length for purposes of original adjustment of the mechanism by means of a screw device 106. The actuator arm 101 causes the under needle movements substantially as in the first form of the invention. Instead of mounting the under needle to move in a vertical plane it is 75 here shown as moving in a slightly inclined plane so as to pass to one side of the upper needle's path below the work and to the other side above the work. Fig. 19 clearly shows the arrangement. The hub 102 already referred to is set at a corresponding incline from the horizontal so that the entire link motion is inclined. This arrangement 80 avoids complication of the link mechanism and no universal joints are necessary other than the two ball and cup devices referred to. Except for the inclined position the following parts are shown substantially as in the first form of the invention, namely, the under needle carrier 71, the links 74, 76 and 90 79, the actuating-extension 81 of link 74, and link 82. The under thread passes out of the actuator link 100 by the exit 108 and thence to a thread-eye 109 above the tension 110 around which latter the thread 100 passes and thence to the take-up lever which swings with the hub 102, the thread passing finally to the eye 112 on the upper part of the stock and thence to the under needle.

Generally speaking the coöperation between 105 the upper and under needles may be as in diagrams 12 to 18. There is the difference, however, that the under needle passes to one side of the upper needle above the work and to its other side below the work. This condition of affairs is illustrated in Figs. 21 to 110 24. Figs. 21 and 22 show the under needle at its highest point, one view being at right angles to the other. Figs. 23 and 24 show both the needles below the work, one view 115 being at right angles to the other. By comparison of Figs. 21 and 23 the under needle is seen behind the upper in the former and in front of it in the latter.

It will thus be seen that there have been 120 described embodiments of the present improvements operating upon the principles and attaining the objects and advantages herebefore referred to.

Since many matters of design, combination, arrangement and other features may be variously modified without departing from the principles hereof no limitation is intended to such features excepting so far as set forth in the appended claims.

What is claimed is:

1. A machine for producing buttonhole stitching with interlocking upper and under threads including in combination, an upper needle for the upper thread, an eye-pointed under needle for the under thread, said upper needle being straight and reciprocable lengthwise in a straight vertical path, said under needle being movable in a curved path in a vertical plane closely adjacent to the upper needle path, a shiftable stock upon which said under needle is mounted, and mechanism operable in all positions of said stock for coöperatively actuating said two needles to interlock the threads alternately above and below the work such that the lower needle may directly enter the loop of thread when held only by the upper needle below the work.
2. A machine for producing buttonhole stitching with interlocking upper and under threads including in combination, an upper needle for the upper thread, an under needle for the under thread, said upper needle being straight and reciprocable lengthwise in a straight vertical path, said under needle being an eye-pointed needle absolutely straight from shank to point and movable in a curved path in a vertical plane closely adjacent to the upper needle path, a shiftable stock upon which said under needle is mounted to move as described, and mechanism operable in all positions of said stock for coöperatively actuating said two needles to cause each needle to directly enter the loop held on the other.
3. A machine for producing buttonhole stitching with interlocking upper and under threads including in combination, an upper

needle for the upper thread, an absolutely straight under needle for the under thread, an under needle carrier, said under needle and carrier being movable in a curved path adjacent to the upper needle path, a shiftable stock upon which said under needle is mounted, and means operable in all positions of said stock for causing said carrier to take a lateral and return movement when below the work whereby the under needle may directly enter the upper loop held only by the upper needle below the work.

4. A machine for producing buttonhole stitching with interlocking upper and under threads including in combination, an upper needle for the upper thread, an under needle for the under thread, the upper needle being absolutely straight and reciprocable lengthwise in a straight path, the under needle being an eye-pointed needle movable in a curved path in a plane parallel to and closely adjacent to the upper needle path, an under needle carrier, said carrier guided in its movements through the work plane by only a plurality of guide links, said guide links, an additional link for causing an extra lateral movement below the work, and mechanism for actuating said needles to interlock the threads both above and below the work by direct coöperation without the interposition of a further looping or spreading means.

In testimony whereof I affix my signature in presence of two witnesses.

FRANKLIN AUGUSTUS REECE.
